UNITED STATES PATENT OFFICE.

ERASTUS L. WALCOTT AND GEORGE J. FISCHER, OF QUINCY, ILLINOIS.

STREET STOP-COCK BOX FOR WATER AND GAS PIPES.

No. 852,359.

Specification of Letters Patent.

Patented April 30, 1907.

Application filed November 11, 1905. Serial No. 286,850.

To all whom it may concern:

Be it known that we, ERASTUS L. WALCOTT and GEORGE J. FISCHER, both citizens of the United States, residing at Quincy, in the county of Adams and State of Illinois, have invented certain new and useful Improvements in Street Stop-Cock Boxes for Water and Gas Pipes; and we do hereby declare the following to be a full, clear, and exact description of the same, reference being had to the accompanying drawings, forming a part of this specification, and to the figures and letters of reference marked thereon.

This invention relates to improvements in appliances or fixtures for facilitating the manipulation of stop cocks such as usually employed in the house mains or between the street mains and houses.

The objects of the invention are to provide exceedingly simple and inexpensive but highly efficient devices capable of use in practically all situations and adapted for use with stop cocks located at widely different depths.

A further object is to provide a structure which shall be inconspicuous in the paved surface of the street not liable to be injured or thrown out of position either by frost or by rough or heavy traffic.

The invention consists in certain novel details of construction and combinations and arrangements of parts all as will be now described and pointed out particularly in the appended claims.

Referring to the accompanying drawings—Figure 1 is a vertical section, with parts in elevation, of a structure embodying the present invention. Fig. 2 is a detail section through the base part in a plane at right angles to Fig. 1. Fig. 3 is a perspective view of the ~~eng~~ parts separated one from the other. Fig. 4 is a detail of the key and guard collar thereon.

Like letters of reference in the several figures indicate the same parts.

The body portion A of the box is as shown, formed of a simple casting of small cylindrical cross-section and having at the lower end a base casting or housing B adapted to fit around or inclose the stop cock C, suitable flanges such as b being extended laterally for holding the body portion firmly in position in the ground. The base casting is slightly larger in diameter than the body A to receive the stop cock but the latter is free to move

or settle to a limited extent independently of the body.

The T-handle c of the stop cock is provided with a coupling or key socket D loosely connected with the T-handle of the stop cock to permit the correct operation of the parts should the box and stop cock be set out of alinement or work out of alinement at any time. The specific connection shown is somewhat in the nature of a universal coupling and is made by forming a slot or recess d in the coupling for the reception of the T-head. One end of the slot has a bridge d' underlying one end of the head so as to hold the coupling against upward movement and a cross pin d² passes under the opposite side of the T-head to hold the parts against complete separation unless the cross pin be intentionally withdrawn. At its upper end, the coupling is formed to enter the lower end of the body of the box with some degree of freedom, and centrally it is provided with a rectangular or other irregular shaped socket or recess E for the reception of the correspondingly formed end of a key F. Instead of being closed at the bottom, the socket or recess E merges into openings E' at the sides of the coupling to provide for the escape of sand or dirt such as is liable to drop into the same and to facilitate the forcible ejection of the dirt by the key the cross sectional area of the side openings is preferably greater than that of the socket and in addition the bottom of the socket and side openings is inclined to permit the dirt to pass through without lodging.

The upper part of the coupling where it enters the body part A is preferably reduced in external diameter for a considerable distance and to prevent complete separation of the stop cock and box or to prevent the stop cock from settling too low, set screws b' are passed through the wall of the body to serve as limiting stops against which the enlarged head or extremity of the coupling will come to rest if the stop cock should tend to drop away.

The upper part of the box is preferably formed by a section G of ordinary gas or water pipe telescoped into the body or lower section and preferably passing through a packing box (to be presently described) on the upper end of the lower section. Complete withdrawal or separation of the upper from the lower section may be prevented by

upsetting the lower end of the upper section, or by bending small parts thereof outward as shown at *g*.

The top flange or surface plate *I* is screw threaded on the upper end of the upper section. Centrally it is provided with a brass bushed threaded aperture for the passage of the key, said aperture being adapted to be closed by an iron plug *K* the head of which lies in a recess in the plate. Said recess is formed with a lateral drainage or cleaning channel or groove *M* to prevent accumulation of water or dirt, or to facilitate cleaning around the plug preliminary to removing the latter for the insertion of the key.

For use in soft sandy or muddy earth, or where an extended surface plate is desired for any reason, a supplemental surface plate *N* is provided, said supplemental plate being 20 in the form of an annulus adapted to fit under the flange or plate on the upper section and having recesses for the ribs *n* on the under side of the latter.

To limit the downward movement of the 25 upper section and to prevent the upper section dropping low enough to injure the stop cock or coupling a collar or flange *O* is formed in the body *A* just above the coupling and in position to engage the lower end of the upper section without interfering with the insertion of the key for turning the cock.

At the upper end of the body section a packing box is provided of such construction as to avoid the use of cores in casting the 35 body section. To accomplish this end, as well as to provide a means whereby the two sections may be held in adjusted position with sufficient firmness for setting etc., the upper end of the body *A* is formed with external ears *h*. Seating on the said upper end is a box *H* for the flexible or elastic packing *H'* and above the box is the gland *H''* having ears *h''*. Bolts *h''* connect the ears *h* and *h''* and serve to hold the parts in place and 45 draw the gland down on the packing with greater or less pressure so as to bind the upper section with a friction grip. The box *H* is preferably centered by small projections *h''* on its under face adapted to enter the upper 50 end of the body *A*.

It will be seen that not only is the structure one well calculated to withstand the action of the surrounding soil under the influence of the elements or changes in temperature but the parts may be made of small section thus the body may be $1\frac{1}{4}$ inches in diameter and $\frac{3}{4}$ pipe may be used for the top section in ordinary house connections. The provision of a socket coupling permits the 55 use of a long key of small diameter and by locating the socket deep in the earth, the liability of meddlesome interference is reduced to the minimum while the operation of the cock by authorized persons provided 60 with a proper key is facilitated.

The use of an iron or steel plug in a brass bushed aperture not only insures the easy opening of the box but the plug itself is strong and being of small value is not liable to be stolen as practice has demonstrated to be the case where brass plugs are used.

To avoid injury to the brass threads in the aperture, the key is provided with a loose flanged collar *P* adapted to pass into the aperture and form a protecting bushing during the manipulation of the key as will be readily understood and said key may be of rectangular form throughout with a socket at one end for manipulating the ordinary T-headed cocks, where boxes and couplings of the present invention are not used.

The radial ribs on the under side of the top plate hold the latter against turning and in addition serve to materially strengthen the plate.

The upper end of the coupling or key socket *D* is of greater external diameter than the internal diameter of the upper section *G*. The socket can, therefore, be made large enough to accommodate a key equal in width 90 to the internal diameter of the upper section *G*.

Having thus described our invention, what we claim as new and desire to secure by Letters Patent, is:—

1. A box for street stop cock connections 95 embodying a lower section having a stop cock housing at its lower end and a packing box at the upper end, a tubular upper section having a surface plate screw threaded on its upper end and telescoping into the lower section through the packing box, a coupling adapted for loose connection with the stop cock, the lower end of said coupling projecting into the stop cock housing and its upper end having a greater external diameter than 100 the internal diameter of the upper section projecting loosely into the lower section, and means whereby said coupling is loosely confined in and guided by the lower section below the lower end of the upper section the 110 construction being such that the coupling may be positioned on the stop cock prior to the placing of the box in position.

2. A box for street stop cocks embodying sections telescoped together, a surface plate 115 secured on the top of the upper section and having a central recess, a central aperture and lateral drainage channel from the recess and a plug for closing the aperture having a head located in the recess when the plug is in 120 position; substantially as described.

3. A box for street stop cocks embodying telescopic sections, a surface plate on the top of the upper section and having radial ribs and a central aperture, a closure for said 125 aperture and a removable annular extension plate having its central opening formed to receive the radial ribs of the top plate; substantially as described.

4. A box for street stop cocks embodying 130

sections telescoped together, a stop cock at the lower end having a loosely connected coupling adapted to be positioned thereon before the box is placed in position over the coupling, said coupling having a reduced intermediate portion and set screws in the lower section of the box loosely engaging in the reduced portion of the coupling, whereby they may be positioned after the box and coupling are positioned to prevent the entire separation of the box and stop cock.

5. A box for street stop cocks embodying telescopic sections each formed of small uniform diameter, and the upper section fitting within the lower section a stop cock coupling below the end of the upper section and having a socketed upper end fitting in and guided by the lower end of the lower section, and a loose connection between the said coupling 15 and stop cock whereby the coupling may

conform to the movements of the box and be held in position to receive the key; substantially as described.

6. A box for street stop cocks embodying telescopic sections, a surface plate on the upper end of the upper section having a central threaded aperture and plug for closing the same and a key having a loose collar adapted to fit in said aperture to protect the threads when the key is manipulated; substantially 25 30 as described.
